UNITED STATES PATENT OFFICE.

CHARLIE BRYANT, OF COIN, IOWA.

BELT-FASTENER.

1,225,572.

Specification of Letters Patent. Patented May 8, 1917.

Application filed April 8, 1916. Serial No. 89,828.

To all whom it may concern:

Be it known that I, CHARLIE BRYANT, a citizen of the United States, residing at Coin, in the county of Page and State of Iowa, have invented certain new and useful Improvements in Belt-Fasteners; and I do hereby declare the following to be a full, clear, and exact description of the invention, such as will enable others skilled in the art 10 to which it appertains to make and use the same.

This invention has for its object to provide a simple and efficient belt fastener embodying means whereby the adjacent ends 15 of a belt may be hingedly connected and present a minimum degree of resistance in passing over a pulley.

With this and other objects in view, the invention consists in the novel construction, 20 combination and arrangement of parts as will be hereinafter specifically described, claimed and illustrated in the accompanying drawing, in which:

Figure 1 represents a plan view of a fragment of a belt, illustrating the improved belt fastener applied thereto,

Fig. 2 represents a transverse sectional view on the line 2—2 of Fig. 1, and

Fig. 3 represents a perspective view of one 30 of the hinge sections removed.

Referring to the drawing, wherein similar reference numerals designate corresponding parts throughout the several views, the numeral 5 indicates a plurality of the fasteners, and 6 the adjacent ends of the belt 35 united by the fasteners 5. Each fastener includes a pair of hinge sections 7 pivotally connected by a hinge rod 8, having angularly directed ends 9, whereby the rod is retained in position with relation to the hinge sections.

Each hinge section 7 is formed at its inner terminal with a hook 10, which embraces the

hinge rod 8 and the opposite end thereof is formed with a longitudinal slit 11 forming 45 a pair of clamping tongues 12.

One of the tongues of each hinge section is extended along the inner surface of the belt 6 and is positioned through a transverse aperture 13 therein, thereby rigidly anchoring the hinge section in position in the belt and the other tongue 12 is extended along the under surface of the belt and disposed oppositely to the first-mentioned tongue 12.

What I claim is:

1. A belt fastener including a body plate having one end reduced and hooked, the opposite end of said hinge section being formed with an inwardly extending longitudinal slit defining a pair of oppositely directed tongues adapted for insertion through a belt, the tongue lying opposite the hook being provided with an angularly directed end adapted to be anchored in one end of a belt. 55

2. In combination, a belt, a plurality of hinge sections secured to the adjacent ends of said belt, a hinge rod connecting said sections, each hinge section including a body plate having one end hooked and engaged 60 with said hinge rod, and formed at its opposite end with an inwardly extending slit defining a pair of tongues, one of said tongues being extended outwardly toward the free end of said belt and along the inner 65 surface of the latter and the other tongue being extended oppositely to the first-mentioned tongue and provided with an angularly directed end penetrating the belt. 70

In testimony whereof I affix my signature 75 in presence of two witnesses.

CHARLIE BRYANT.
